UNITED STATES PATENT OFFICE.

ALBERT WAHLE, OF BROOKLYN, NEW YORK.

DESIGN FOR A BOWL FOR A LIGHTING-FIXTURE.

52,418.

Specification for Design. Patented Sept. 10, 1918.

Application filed March 15, 1918. Serial No. 222,741. Term of patent 7 years.

To all whom it may concern:

Be it known that I, ALBERT WAHLE, a citizen of the United States, and a resident of the borough of Brooklyn, county of Kings, city and State of New York, have invented a new, original, and ornamental Design for a Bowl for Lighting-Fixtures, of which the following is a specification, reference being had to the accompanying drawing, forming part hereof.

The said drawing is a front view of a

bowl for a lighting fixture showing my new design.

I claim:

The ornamental design for a bowl for a lighting fixture, as shown.

In witness whereof I have hereunto signed my name this 13th day of March, 1918.

ALBERT WAHLE.

Witness:

ELIZABETH G. WELSH.
